UNITED STATES PATENT OFFICE.

GEORGE BAUER, OF MILWAUKEE, WISCONSIN.

SOAP-CUTTER.

1,319,371.

Specification of Letters Patent.

Patented Oct. 21, 1919.

Application filed April 17, 1919. Serial No. 290,813.

To all whom it may concern:

Be it known that I, GEORGE BAUER, a citizen of the United States, and resident of Milwaukee, in the county of Milwaukee and

5 State of Wisconsin, have invented certain new and useful Improvements in Soap-Cutters; and I do hereby declare that the following is a full, clear, and exact description thereof.

10 My invention relates to new and useful improvements in devices for slicing or flaking soap or similar material.

It is in general the object of my invention to simplify and otherwise improve the structure and to increase the efficiency of devices of this character, particularly with respect to the provision of an automatic feed for the work material whereby to procure an even cutting operation thereof.

20 It is further my object to provide a compact and efficient household device embodying the foregoing characteristics and which may be readily mounted on a suitable support and manipulated to procure a rapid 25 and even slicing or flaking operation on soap or other material.

With the above and other objects in view, which will be apparent as the description proceeds, my invention resides in the novel 30 features of construction, combination and arrangement of parts as hereinafter described and defined by the appended claim, it being understood that changes in the precise embodiment might be made by those 35 skilled in the art, without departing from the spirit of the invention.

In the accompanying drawings:

Figure 1 is a longitudinal, sectional view 40 through a soap cutting device embodying my invention.

Fig. 2 is a transverse sectional view there- through on a plane indicated by the line 2—2 of Fig. 1, and

Fig. 3 is an end view of the device.

45 Referring now more particularly to the accompanying drawings, the present embodiment of the invention includes a skeleton chamber comprising longitudinal angle sections 5 connected at their ends by trans- 50 verse sections 6. Clamp legs 7 depend from the lower sections 5 for seating engagement on the edge of the table or other support α and a U-shaped screw bracket 9 depends from the legs for the reception of a clamp- 55 ing screw 10 whereby the device may be firmly clamped on the support.

Upstanding bearing lugs 11 are formed on the top transverse sections 6 and a screw shaft 12 is journaled in these lugs, having one end offset to form a crank handle 13. 60 The other end of the shaft is squared for engagement in a correspondingly squared knife hub 14 having a pair of radial legs 15 movable across the adjacent end of the chamber, which is open to permit free feed- 65 ing movement of soap or other material therefrom. To form a guard for the knife blades 15, preventing possible injury to the operator and also preventing damage to the knife blades, a circular plate enlargement 16 70 is formed on the adjacent end of the chamber, the diameter of this plate being slightly greater than the span of the blades, which move closely adjacent thereto. A traveling sleeve 17 is threaded on the screw shaft 12 75 and this sleeve carries a depending follower head 18 which extends transversely in the chamber and has forwardly extended wings 19 at its ends slidably on trackways formed by the edges of the lower angle sections 5. 80 For clamping a bar of soap or other work material to this follower head whereby to prevent accidental forward movement due to jarring or other force, a screw 20 is threaded in one of the wings 19 and carries 85 a clamp head 21 adapted to clamp the bar of soap or the like against the other wing 19.

An exceedingly simple device has thus been provided which may be readily operated to procure a rapid and even slicing 90 operation on soap or other work material, the work material being fed forward by the screw shaft 12 as the knife blades thereof are rotated.

While I have shown and described a preferred embodiment of my invention it will be appreciated that various changes and modifications of structure may be employed to meet differing conditions of use, the chamber of the device comprising essentially a slideway for the work material and a frame for supporting the operating shaft. 95

What is claimed is:

A device of the class described including a skeleton chamber having longitudinal edge 105 bars connected together at their ends, means for supporting said chamber, a screw shaft journaled on and extending longitudinally of the chamber, a knife on the shaft at one end of the chamber, a sleeve threaded on the 110 shaft, a follower head carried by the sleeve and depending into the chamber, arms on

said head extending transversely of the chamber and having their outer end directed longitudinally of the chamber to form wings slidable on the lower edge bars of the 5 skeleton chamber, a clamp screw threaded through one of said wings and a clamp head on the inner end of said screw adapted to

clamp work material between said clamp head and the opposite wing.

In testimony that I claim the foregoing 10 I have hereunto set my hand at Milwaukee, in the county of Milwaukee and State of Wisconsin.

GEORGE BAUER.
